KEY OPERATED LOCK MECHANISM

Leon E. Willett and Raymond G. Baker, Detroit,
Mich., assignors to Chamberlin Company of
America, Detroit, Mich., a corporation of Mich-
igan

Application June 20, 1949, Serial No. 100,106

13 Claims. (Cl. 70—355)

1

This invention relates generally to key operated locking mechanism of the type suitable for use on swinging closures, such for example, as screens, windows and doors.

It is one of the objects of this invention to provide a lock having latching tumblers releasable from either side of the lock by a bit type key and having provision for resisting unauthorized operation of the lock by instruments other than the key.

Another object of this invention is to provide a lock having a freely rotatable central hub and having an operating member supported for rotation about the hub axis. In accordance with this invention the operating member is normally held against rotation by a tumbler extending along one side of the hub and pivoted intermediate the ends on the operating member for rocking movement about an axis substantially parallel to the hub axis. One end of the tumbler has an abutment urged by spring means into latching engagement with a fixed shoulder to hold the operating member against rotation, and the other end of the tumbler has a cam positioned to register with a land on the key bit. The arrangement is such that rotation of the key in one direction engages the land with the cam, and rocks the tumbler against the action of the spring means to release the abutment from the shoulder. As a result continued rotation of the key in the above direction imparts a rotative movement of the operating member in a corresponding direction.

It is still another object of this invention to provide a plurality of tumblers pivoted on the operating member in juxtaposition to each other for rocking movement independently of one another and respectively coacting with a corresponding number of lands on the key bit to release the operating member. According to the present invention the tumblers and lands on the key bit are symmetrically arranged to enable releasing the tumblers by the key regardless of whether the key is inserted into the lock from the inner or outer sides of the latter.

A still further feature of this invention is to provide a lock of the above general type wherein provision is made on the key engaging ends of the tumblers for engaging a second fixed shoulder to latch the operating member in the event one or more of the tumblers are rocked beyond their released positions. This feature renders it extremely difficult to release the tumblers by instruments other than the key intended for this purpose.

The foregoing as well as other objects will be

2

made more apparent as this description proceeds, especially when considered in connection with the accompanying drawings, wherein:

- Figure 1 is an exploded view showing the various parts of the lock assembly in perspective;
Figure 2 is a fragmentary sectional view showing one application of the lock assembly;
Figure 3 is a cross sectional view taken on the line 3—3 of Figure 2;
Figure 4 is a sectional view taken on the line 4—4 of Figure 3;
Figures 5 to 9 inclusive are sectional views showing the relationship of the various parts of the lock in different positions; and
Figure 10 is a sectional view showing the manner in which the lock operates to prevent unauthorized release by instruments other than the key.

The lock assembly forming the subject matter of this invention has many and diversified uses. However, it is particularly suitable for use in connection with either detention screens or doors, and is shown herein for the purpose of illustration as installed on a detention screen door structure.

The various parts of the lock assembly are shown in detail in Figure 1 of the drawings, and it will be noted that these parts are relatively simple in design, enabling the same to be economically manufactured on a production basis. Certain of the above parts cooperate with one another to form a case 10 of a size to permit installation of the lock in a small space. In detail the parts forming the case comprise end plates 11 and 12 separated from one another by an annular spacer in the form of a split ring 13. The ring 13 has circumferentially spaced lugs 14 projecting from opposite edges thereof, and engageable in aligned openings 15 formed in the end plates to properly position the ring relative to these plates. The end plates are secured together with the spacer 13 clamped therebetween by machine screws 16 which respectively extend through the aligned openings 15 in the plates.

The end plates are further formed with substantially centrally disposed aligned openings 17 and with slots 18 which extend from corresponding sides of the openings 17. The openings 17 and slots 18 coact to form key holes of a shape to freely receive a bit type key 19 to be presently described. In this connection it is pointed out that the end plate 12 serves as a mounting plate for securing the lock assembly to suitable supporting structure, and is formed with a second slot 20. The slot 20 extends outwardly from the

opening 17 in diametrically opposed relationship to the slot 18, and renders the mounting plate 12 of the case adaptable for either right or left hand installations. The plate 11 is symmetrical, and as a consequence, may be used for either right or left hand installations.

Freely rotatably supported in the case 10 between the end plates 11 and 12 is a hub 21. The opposite ends 22 of the hub 21 are reduced in diameter, and are respectively rotatably supported in the openings 17 in the end plates. The hub 21 is bored to provide a central opening 23 therethrough, and is formed with a slot 24 extending for the full length of the hub from one side of the opening 23 to the periphery of the hub. The opening 23 is of sufficient diameter to freely receive the pin 25 of the key shank 19, and the slot 24 is adapted to register with the slots 18 in the end plates to freely receive the bit 26, which projects laterally outwardly from the pin or key shank.

A pair of operating members 27 and 28 are respectively rotatably supported in the case 10 adjacent the inner surfaces of the end plates 11 and 12. The operating members have arcuate portions 29, and the hub 21 has axially spaced annular stops 30 which form bearing surfaces for respectively engaging the inner surfaces of the arcuate portions 29 on the operating members 27 and 28.

A spacer block 31 is interposed between the operating members at one end of the arcuate portions 29, and is secured to both operating members by a machine screw 32. Also the operating members are angularly located with respect to one another by pins 33 and 34. The pin 33 extends through the spacer block 31 and the opposite ends thereof project into aligned openings 35 formed in the operating members. The pin 34 is diametrically opposed with respect to the pin 33 and also extends through aligned openings 36 in the operating members. Thus the operating members and the spacer block are rotatable as a unit relative to the hub 21 about the axis of the latter.

The operating members are also formed with lugs 37 which project laterally outwardly from the ends of the operating members opposite the ends thereof which are clamped to the spacer block 31 by the screw 32. The lugs 37 respectively project through arcuate recesses 38 formed in opposite edges of the annular spacer 13 at one side of the latter. Also the lugs 37 have aligned openings 39 therethrough for attachment to suitable latch mechanism to be hereinafter described.

The operating members are normally held against rotation about the axis of the tube 21 by a plurality of tumblers. The number of tumblers may be varied, but for the purpose of illustration, three tumblers are shown, and are designated in the drawings by the numerals 40, 41 and 42. The tumblers are generally arcuate in configuration, and are located within the case 10 between the operating members in juxtaposition to one another at one side of the hub 21. As shown particularly in Figure 1 of the drawings, the tumblers have aligned openings 43 intermediate the ends thereof for receiving the positioning pin 34, and are thereby capable of independent rocking movement about the axis of the pin 34, which is parallel to the axis of the hub 21.

The tumblers have outwardly extending lugs 44 at corresponding ends, and these lugs are adapted to extend through an opening 45 formed in the

adjacent side of the annular spacer 13. One side of the opening 45 provides a shoulder 46 for engagement by the lugs 44. When the lugs are positioned to engage the shoulder 46, rotation of the operating members 27 and 28 is prevented, and the lugs are normally urged to this position by means of an arcuate spring 47. One end of the spring 47 is engaged in a slot 48 formed in one end of the spacer block 31. The opposite end of the spring 47 is formed to provide three fingers 49, which respectively engage the tumblers at the inner sides of the lugs 44 to urge the latter outwardly into the opening 45. In this connection it will be noted from Figure 1 of the drawings that the tumblers are provided with notches 50 which form seats for the spring fingers 49.

The ends of the tumblers opposite the lugs 44 are formed with cams 51, and these cams are positioned for engagement with the bit 26 on the key when the latter is inserted in the lock as shown in Figures 4 to 9 inclusive. The end tumblers 40 and 42 are identical in design, and the cams 51 assume the same relationship to the bit 26 on the key. The intermediate tumbler 41, on the other hand, is of somewhat different design in that the cam 51 is actually offset inwardly toward the hub 21. It will be observed from Figure 1 of the drawings that the hub 21 is provided with an annular groove 51 of sufficient size to freely accommodate the inwardly projecting cam 51 on the intermediate tumbler 41. It will also be seen from Figure 7 of the drawings that the intermediate tumbler 41 has an arcuate inwardly extending projection 52 intermediate the ends which engages in the groove 51 and serves to position the intermediate tumbler 41 centrally between the end tumblers 40 and 42.

The bit 26 on the key is shown in Figure 4 of the drawings as having a land 53 intermediate the ends thereof and as having lands 54 and 55 symmetrically arranged at opposite sides of the land 53. The lands 54 and 55 are spaced equal distances outwardly from the axis of the key, and the land 53 is spaced a lesser distance from the axis of the key. The arrangement is such that insertion of the key into the lock from either side of the latter registers the lands 55 and 54 with the cams 51 on the end tumblers 40 and 42 respectively, and the land 53 registers with the cam 51 on the intermediate tumbler 41. Thus rotation of the key in a direction toward the cam ends of the tumblers engages the lands on the bit 26 with the cams 51 on the respective tumblers, and swings the tumblers about the axis of the pin 34 to disengage the lugs 44 from the shoulders 46, as shown in Figure 8 of the drawings. Continued rotation of the key in the above named direction imparts a rotative movement to the operating members 27 and 28 in a corresponding direction in the manner clearly indicated in Figure 9 of the drawings. It is to be noted that when the key is in the position shown in Figure 9 of the drawings, it cannot be withdrawn, and is held in the lock until returned to the position shown in Figure 5 of the drawings. When in this latter position the lugs 44 on the tumblers again register with the opening 45, and the tumblers are actuated by the spring 47 to extend the lugs through the opening 45 into engagement with the shoulder 46. It will be understood that upon return movement of the key from the position shown in Figure 9 to the position shown in Figure 5, the bit on the key engages the spacer block 31.

and adjacent ends of the operating members to return the latter to their latched positions.

Attention is now called to the fact that each tumbler has an outwardly extending projection 56 at the cam end, and the annular spacer 13 has an opening 57 therethrough which registers with the projections 56 in the latched position of the lock shown in Figures 5 to 7 inclusive. During normal operation of the lock, the projections 56 are always spaced inwardly from the opening 57, and do not interfere with manipulation of the lock by the key. However, should an attempt be made to "pick" the lock, or in other words, to move the tumblers to their released positions by inserting an instrument 59 (Figure 10) through the key hole, the projections 56 on at least one of the tumblers would, in all probability, extend through the opening 57 in the manner shown in Figure 10. Thus rotation of the operating members to their released positions is prevented by engagement of the projection or projections extending into the opening 57 with a shoulder 60 forming one side of the opening 57.

Referring now to Figures 2 and 3 of the drawing, it will be noted that the lock is mounted on an upright frame bar 61, which in the present instance, forms the swinging side of a suitable door. The outer edge of the bar 61 is formed with a lateral flange 62 terminating in an inwardly extending flange 63. The inner edge portion of the bar 61 is curved laterally, and terminates in an outwardly extending flange 64. A plate 65 is welded or otherwise secured to the flange 63, and the inner edge portion of the plate has an outwardly extending flange 66 which co-acts with the flange 64 to receive the adjacent edge portion of a screen or panel 67 therebetween.

The lock is supported in the space between the bar 61 and plate 65 with the lock plate 12 seated on the inner surface of the bar 61. As shown in Figure 1 of the drawings one side of the plate 12 is formed with diverging arms 68 having lugs 69 at the extremities extending through slots 70 formed in the flange 62 of the frame bar 61. The opposite side of the plate 12 has spaced laterally extending arms 71 which have a wedging engagement with the inner edge of the flange 64 in the manner clearly shown in Figures 3 and 4 of the drawings. The arms 71 are connected by a web 50 72 which is bowed laterally outwardly to occupy a position beneath the flange 64 after the lock is positioned on the bar 61. The bar 61 and in the present instance, the plate 65 are formed with key hole slots 73 in registration with the key 55 holes in the lock.

The lugs 37 on the operating members 27 and 28 are connected to the inner ends of a pair of rods 75 by a pin 76 extending through the aligned openings 39 in the lugs 37. The rods 75 extend in opposite directions from the pin 76 along the inner side of the flange 65 and the outer ends of the rods are respectively pivotally connected to the inner ends of slides 77. The slides 77 are supported by guides 78 for sliding movement in the direction of length of the frame bar 61, and are connected to latch members in the form of bolts 79. The bolts are respectively supported by the guides 78 for sliding movement in opposite directions perpendicular to the path of sliding movement of the slides 77, and are of sufficient length to project through aligned openings 80 and 81 formed in the flange 62 and adjacent fixed frame structure 82 to lock the door in its closed position.

As shown in Figure 2 of the drawings the inner end portions of the bolts 79 are formed with slots 83 through which the slides 77 extend, and the latter are connected to the bolts 79 by pins 84 extending in a direction transverse to the bolts through slots 85 formed in the slides 77. The upper end portions of the slots 85 extend for some distance along the respective slides at right angles to the pins 84, and the opposite ends of the slots 85 flare laterally to the inner edge of the slides 77 to form inclined cam faces 86.

When the operating members 27 and 28 are locking in the positions shown in Figures 5 to 7 inclusive of the drawings, the bolts 79 are extended to their operative positions shown in Figure 2 of the drawings, and the pins 84 are engaged in the straight portions of the slots 85. Thus the bolts 79 cannot be moved inwardly to their released positions by applying a force directly on the bolts. On the contrary the bolts can only be released by manipulating the lock with the proper key. In this connection it will be noted that when the lock is operated by the key, the operating members are rocked to the position shown in Figure 9 of the drawings. As the operating members are rocked to the position shown in Figure 9, the slides 77 are moved upwardly by the rods 75 to engage the cam surfaces 86 with the pins 84 and retract the bolts 79 to their released positions. Of course return movement of the operating members to their locked positions shown in Figure 5 moves the slides 77 downwardly relative to the pins 84 on the bolts 79 and moves bolts outwardly through the registering openings 81 in the fixed frame 82.

What we claim as our invention is:

1. A lock assembly of the type adapted for operation by a key having a shank and a bit projecting laterally from the shank adjacent one end of the latter, comprising a case having plates secured together in lateral spaced relationship and one of the plates having a key receiving slot, a hub rotatably supported by the plates and positioned between the latter, said hub having an opening for receiving the key shank and having a slot registerable with the slot in said one plate for receiving the key bit, a member supported in the case for rotation about the hub axis, a tumbler pivoted intermediate the ends on the member for rocking movement about an axis substantially parallel to the hub axis, abutment means on the tumbler at one side of the pivot and engageable with a shoulder fixed relative to the case to prevent rotation of said member, spring means acting upon the tumbler to urge the abutment means into engagement with said shoulder, cam means on the tumbler at the opposite side of the pivot and adapted to respectively coact with a land on the key bit upon rotation of the key in one direction to rock the tumbler about its pivot against the action of the spring means and disengage the abutment means from the shoulder, a second abutment means at the cam end of the tumbler, and means fixed relative to the case engageable with the second abutment means upon excessive rocking movement of the tumbler toward its released position to prevent rotation of said member by the tumbler.

2. The lock assembly set forth in claim 1 in which both plates of the case have key receiving slots to enable inserting the key into the case from either the inner or outer sides of the case, and in which the cam means on the tumbler are symmetrically arranged to engage the land on the key to release the first named abutment

means on the tumbler from said shoulder regardless of whether the key is inserted into the lock from the inner or outer sides thereof.

3. A lock assembly of the type adapted for operation by a key having a shank and having a bit projecting laterally from the shank adjacent one end of the latter, comprising a casing having laterally spaced plates provided with aligned openings, a hub located between the plates and having the opposite ends respectively freely rotatably supported in the aligned openings in said plates, said hub having an opening for receiving the key shank and having a slot registerable with slots in said plates for receiving the key bit, an operating member supported in the case for rotation about the axis of the hub, a plurality of tumblers pivoted intermediate the ends on the operating member to one side of the hub for rocking movement independently of one another about an axis substantially parallel to the hub axis, abutment means on each tumbler at one side of the pivot axis and engageable with a shoulder fixed relative to the case to prevent rotation of the operating member, spring means normally urging the abutment means into engagement with said shoulder, cam means on each tumbler at the opposite side of the pivot axis and adapted to respectively coact with lands on the key bit upon rotation of the key in one direction to rock the tumblers about the pivot axis against the action of said spring means and disengage the abutment means on the tumblers from said shoulder, said cam means being symmetrically arranged to enable releasing the abutment means on the tumblers from said shoulder regardless of whether the key is inserted into the lock from the inner or outer sides thereof.

4. A lock assembly of the type adapted for operation by a key having a shank and having a bit projecting laterally from the shank adjacent one end of the latter, comprising a case having laterally spaced plates provided with aligned openings, a hub located between the plates and having the opposite ends respectively freely rotatably supported in the aligned openings in said plates, said hub having an opening for receiving the key shank and having a slot registerable with slots in said plates for receiving the key bit, an operating member supported in the case for rotation about the axis of the hub, a plurality of tumblers pivoted intermediate the ends on the operating member to one side of the hub for rocking movement independently of one another about an axis substantially parallel to the hub axis, abutment means on each tumbler at one side of the pivot axis and engageable with a shoulder fixed relative to the case to prevent rotation of the operating member, spring means normally urging the abutment means into engagement with said shoulder, cam means on each tumbler at the opposite side of the pivot axis and adapted to respectively coact with lands on the key bit upon rotation of the key in one direction to rock the tumblers about the pivot axis against the action of said spring means and disengage the abutment means on the tumblers from said shoulder, second abutment means on each tumbler at the cam ends of the latter, and means fixed relative to the case engageable with the second abutment means upon excessive rocking movement of the tumblers toward their released positions to prevent rotation of the operating member by said tumblers.

5. The lock assembly set forth in claim 4 in which the cams on the tumblers are symmet-

rically arranged to enable the key to release the tumblers from said shoulder regardless of whether the key is inserted into the lock from the inner or outer sides of the lock.

6. A lock assembly of the type adapted for operation by key having a shank and having a bit projecting laterally from the shank adjacent one end of the latter, comprising a case having laterally spaced plates and having an annular spacer located between the plates in fixed relation thereto, a hub located between the plates and having the opposite end portions freely rotatably supported in aligned openings in said plates, said hub having an opening therethrough for receiving the key shank and having a slot registerable with slots in said plates for receiving the key bit, operating members respectively rotatably supported in the case on opposite end portions of the hub and having portions projecting laterally through arcuate slots in the spacer, a tumbler located between the operating members to one side of the hub and pivoted intermediate the ends on the operating members for rocking movement about an axis substantially parallel to the hub, abutment means on the tumbler at one side of the pivot axis and engageable with a shoulder on the spacer to prevent rotation of the operating members, spring means normally urging the abutment means into engagement with said shoulder, and cam means on the tumbler at the opposite side of the pivot axis and adapted to respectively coact with a land on the key bit upon rotation of the key in one direction to rock the tumbler about its pivot axis against the action of the spring means and thereby disengage the abutment means on the tumbler from said shoulder.

7. The lock assembly set forth in claim 6 characterized in that a second abutment means is provided on the cam end of the tumbler and a second shoulder is provided on the spacer for engagement with the second abutment means upon excessive rocking movement of the tumbler toward its released position to prevent rotation of the operating members by said tumbler.

8. A lock assembly of the type adapted for operation by key having a shank and having a bit projecting laterally from the shank adjacent one end of the latter, comprising a case having laterally spaced plates and having an annular spacer located between the plates in fixed relation thereto, a hub located between the plates and having the opposite end portions freely rotatably supported in aligned openings in said plates, said hub having an opening therethrough for receiving the key shank and having a slot registerable with slots in said plates for receiving the key bit, operating members respectively rotatably supported in the case on opposite end portions of the hub and having portions projecting laterally through arcuate slots in the spacer, a plurality of tumblers located in juxtaposition between the operating members and pivoted intermediate the ends thereof on the operating members for rocking movement independently of one another about an axis substantially parallel to the hub axis, abutment means on each tumbler at one side of the pivot axis engageable with a shoulder on the spacer to prevent rotation of the operating members, spring means acting on the tumblers to urge the abutment means thereon into engagement with said shoulder, cam means on each tumbler at the opposite side of the pivot axis and adapted to respectively coact with lands on the key bit upon rotation of

the key in one direction to rock the tumblers about their pivot axes against the action of the spring means and thereby disengage the abutment means on the respective tumblers from said shoulder, the said cam means being symmetrically arranged to release the tumblers from said shoulder regardless of whether the key is inserted into the lock from the inner or outer sides thereof.

9. The lock assembly of claim 8 characterized in that second abutment means is provided at the cam end of each tumbler for engagement with a second shoulder on the spacer upon excessive rocking movement of the tumblers toward their released positions to prevent rotation of the operating members by the tumblers.

10. A lock assembly comprising a case, a hub freely rotatably supported in the case, said hub having an opening therethrough for receiving a key shank and having a slot for receiving a key bit, a member supported in the case for rotation about the hub axis, a plurality of tumblers arranged in juxtaposition to one another in the case and pivoted intermediate the ends on said member to one side of the hub for rocking movement about an axis substantially parallel to the hub axis, abutment means on each tumbler at one side of the pivot axis and engageable with a shoulder fixed relative to the case to prevent rotation of said member, spring means acting on the tumblers and normally urging the abutment means into engagement with said shoulder, cam means on each tumbler at the opposite side of the pivot axis and adapted to respectively engage lands on the key bit upon rotation of the key in one direction to rock the tumblers about the pivot axis against the action of the spring means and disengage the abutment means on the tumblers from said shoulder.

11. A lock assembly comprising a case, a hub freely rotatably supported in the case, said hub having an opening therethrough for receiving a key shank and having a slot for receiving a key bit, a member supported in the case for rotation

about the hub axis, a pair of tumblers pivoted intermediate the ends thereof on said member to one side of the hub for rocking movement about an axis substantially parallel to the hub axis and having cam portions at one side of the pivot axis adapted to respectively engage lands on the key bit, an intermediate tumbler between the pair of tumblers and pivoted between the ends thereof on the pivot axis of said pair of tumblers, cam means on the intermediate tumbler adapted to engage another land on the key bit, abutment means on each tumbler at the opposite side of the pivot axis and engageable with a shoulder fixed relative to said case to prevent rotation of the member, and spring means normally urging the abutment means into engagement with said shoulder.

12. The latch assembly defined in claim 11 in which the case has inner and outer walls slotted to enable inserting the key into the hub from either the inner or outer sides of the case, and in which the cams on the tumblers are symmetrically arranged with respect to the lands on the key bit to enable releasing the abutment means on the tumblers from said shoulder by the key regardless of whether the key is inserted into the lock from the inner or outer sides thereof.

13. The latch assembly defined in claim 11 in which the tumblers are provided with abutment means adjacent the cams thereon for engagement with a second shoulder fixed relative to the case upon excessive rocking movement of the tumblers toward their released positions to prevent rotation of said member by the tumblers.
